SPECIMEN GRIPS

John C. McClelland, Flourtown, Pa., assignor to Tatnall Measuring Systems Company, Philadelphia, Pa., a corporation of Delaware

Application October 28, 1957, Serial No. 692,930

4 Claims. (Cl. 73—103)

This invention relates to specimen grips, especially for testing machines, and has for an object the provision of improvements in this art.

One of the particular objects is to provide grips which act rapidly and effectively to grip a specimen.

Another object is to provide grips which furnish free access from the front for the insertion and removal of specimens.

Another object is to provide grips which retain the ends of a specimen, broken or otherwise, until released.

Another object is to provide grips which are free from backlash or loose movement when the loading is reversed as in alternate tension and compression testing.

Another object is to provide grips which accurately center the ends of the specimen.

Another object is to provide grips which can be quickly assembled and separated.

Another object is to provide grips which are simple and inexpensive and which can readily be applied to existing machines.

The above and other objects and advantages will be apparent from the following description of an exemplary embodiment, reference being made to the accompanying drawings wherein:

Fig. 1 is a front elevation of a testing machine having grips which embody the present invention;

Fig. 2 is an enlarged elevation and vertical section of the upper grip mechanism of the machine; the section being taken on the line 2—2 of Fig. 4;

Fig. 3 is a vertical section taken on the line 3—3 of Fig. 4;

Fig. 4 is a horizontal section taken on the line 4—4 of Fig. 2;

Fig. 5 is an enlarged front elevation of the grip shown in Fig. 4;

Fig. 6 is a left side elevation of the parts shown in Figs. 4 and 5;

Fig. 7 is a right side elevation of the parts shown in Figs. 4 and 5; and

Fig. 8 is a wiring diagram.

In Fig. 1, a complete testing machine is shown to illustrate how the grips of the present invention are used thereon. It comprises a base 10, a table 11, columns 12, a movable crosshead 13, a top column-connecting beam 14, and rams 15 which have movable cylinders to raise and lower the table, the pistons being secured to the columns which are anchored to the base. The crosshead can be secured at any point along the columns.

Upper and lower grips 16, with which the present invention is particularly concerned, are secured to the crosshead 13 and table 11 respectively. The grips are alike but are reversed in position so the description of one will serve for both.

A load cell unit 17 carried by the crosshead measures the strains in the specimen. As shown in Fig. 2, the upper grip is secured to the load cell by spaced flexible plates 18 and 19, an intermediate spacer 20, and securing

2

means including headed screws 21 which secure the plate 18 to the crosshead, screws 22 which secure the grip unit to the spacer 20, screws 23 which secure the plate 19 to the crosshead, and screws 24 which secure the spacer 20 to the inner portion 25 of the load cell.

The grip comprises a frame 30 which may be made as an integral unit but which is here shown as a multipart assembly comprising an upper plate 31, a lower plate 32, intermediate spacers 33 keyed in position by recessed key bars 34 and edge connecting plates 35 and 36 secured by headed screws 37. The edge plate 35 is firmly held in position by keys 38 extending around its periphery at a distance from the edges. The upper and lower plates 31 and 32 are rigidly secured together by bolts 39.

The upper and lower plates 31 and 32 and the spacers 33 form between them a transverse guideway for the gripping mechanism which here includes rough faced grip blocks 42 and pusher blocks 43 therebehind. The blocks are tapered on their engaging surfaces so that when a specimen is gripped the grip blocks will be pressed upward against the top plate 31 and the pusher blocks will be pressed down against the lower plate 32. This avoids all backlash or loose movements when the loads are reversed.

The grip blocks and pusher blocks are loosely entrained by headed screws 44 threaded in one block which fit loosely in oversized holes of the companion block. This provides that the grip blocks will be pulled back with the pusher blocks when the latter are retracted.

One pusher block 43 is moved in and out to a set index position for each size specimen by any suitable means, such, for example, as a screw 45 which is threaded in the side plate 36 and which has a retaining turn fit of its head 46 in an undercut recess in the pusher block.

The other pusher block 43 is moved in by power means, here a fluid operated expandable bag 50, and is moved back outward by suitable power means, here shown as springs 51, disposed in recesses of cooperating shoulders (Fig. 4) of the pusher block and the spacer blocks 33. A source of pressure fluid is connected to the bag 50 by a fluid line 52 suitably connected to the bag as by being vulcanized thereto or secured by a nipple. The connection is shown on the side of the bag but may be made on the back if expansion and contraction of the side should cause any difficulty, such as leakage.

The outward movement of the blocks is limited by engagement of the grip blocks with the edges of the opening 53 in the plate 32 through which the ends of the grip blocks project. The fluid bag is prevented from expanding into the spaces around the pusher block by a thin outer sealing frame 54 of angular cross section. The outer edges of the frame expand into contact with the pusher block and guide sides to prevent entry of the bag even when the block is not fitted to close tolerances in the guideway.

Means are provided for gaging the stop position of the manually adjusted blocks so that the specimen will be accurately centered transversely. As shown in Fig. 1, the manual adjusting screw at the top is arranged on one side and at the bottom is arranged at the opposite side. When the screws are equally adjusted the grip blocks will stand at equal distances from a vertical central plane running from front to back. By making the total distance of both equal to the transverse width of the specimen the specimen will be disposed in vertical position. To show the setting there is secured alongside each screw a marked gage plate 56 and the end of the screw around its circumference is provided with division markings, as shown in Fig. 7.

The adjustment may be indicated more precisely by having the screws move a slider 58 of a rheostat 59 as they are turned in and out. By placing these variable

rheostat resistances in a bridge circuit, as shown in Fig. 8, the equality of setting is established when the bridge reading is zero. In this circuit the upper and lower grip resistors 59 are respectively indicated as R1 and R2 and the standard resistances of the bridge are indicated as R3 and R4. The slider is moved by a head flange 60 secured to the end of the screw.

Means are provided for adjusting the position of the back edge of the specimen at top and bottom to assure that the back edge is disposed vertically. The means herein shown comprise screw gages 63 secured to the grip holder at the rear center. A vernier adjustment and scale is provided as on micrometers.

The front of the grip frames is open, as shown in Fig. 4, to permit the specimen to be quickly inserted until it is brought into contact with the adjustable back stops 63. With the opposite sides, top and bottom, first manually adjusted for the selected specimen and a specimen inserted against the back stops, the fluid bags are simultaneously filled with pressure fluid and the specimen is immediately gripped for testing. The specimen ends will be retained until the fluid pressure is relieved and the springs cause the grip blocks on one side at each end to retract and release the specimen.

It is thus seen that the invention provides simple, sturdy, reliable, accurate and easily operated means for gripping specimens for testing.

While one embodiment has been described for purposes of illustration it is to be understood that there may be various embodiments and modifications within the general scope of the invention.

What is claimed is:

1. Specimen grips comprising in combination, a frame having a transverse guideway, said guideway including spaced upper and lower block retaining guide surfaces, gripper jaw blocks slidable along said guideway toward and from a specimen center line, pusher blocks loosely entrained with said gripper blocks and also mounted for sliding movement along said guideway, said gripper and pusher blocks being guided by said retaining surfaces above and below and having inclined mating surfaces so that one will be pushed up against one of said retaining surfaces and the other will be pushed down against the other of said retaining surfaces when clamped on a specimen, and means for moving said pusher blocks in and out.

2. Apparatus as set forth in claim 1, wherein said moving means on one side comprises an adjustable part connected in push-pull relationship with one of said pusher blocks and which can be set to position and wherein the

moving means for the pusher block on the other side comprises a power operated device for moving it inward, and springs for moving it outward.

3. Specimen grips comprising in combination, a frame having a transverse guideway, said guideway including spaced upper and lower block retaining guide surfaces, gripper jaw blocks slidable along said guideway toward and from a specimen center line, pusher blocks loosely entrained with said gripper blocks and also mounted for sliding movement along said guideway, said gripper and pusher blocks being guided by said retaining surfaces above and below and having inclined mating surfaces so that one will be pushed up against one of said retaining surfaces and the other will be pushed down against the other of said retaining surfaces when clamped on a specimen, and means for moving said pusher blocks in and out, spaced grips being provided for opposite ends of a specimen, settable adjusting means for the pusher blocks at opposite sides at opposite ends, and power means at opposite ends for operating the other pusher blocks at opposite sides.

4. Specimen grips comprising in combination, a frame having a transverse guideway, said guideway including spaced upper and lower block retaining guide surfaces, gripper jaw blocks slidable along said guideway toward and from a specimen center line, pusher blocks loosely entrained with said gripper blocks and also mounted for sliding movement along said guideway, said gripper and pusher blocks being guided by said retaining surfaces above and below and having inclined mating surfaces so that one will be pushed up against one of said retaining surfaces and the other will be pushed down against the other of said retaining surfaces when clamped on a specimen, and means for moving said pusher blocks in and out, spaced grips being provided for opposite ends of a specimen, settable adjusting means for the pusher blocks at opposite sides at opposite ends, and power means at opposite ends for operating the other pusher blocks at opposite sides.
